Primary Examiner — Jack Reickel*Assistant Examiner* — Sydney M Evans(74) *Attorney, Agent, or Firm* — Rosenberg, Klein & Lee(57) **CLAIM**

The ornamental design for a lock device, as shown and described.

DESCRIPTION

FIG. 1 is a front side perspective view showing our new design for lock device;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top view thereof;

FIG. 7 is a bottom view thereof; and,

FIG. 8 is a top perspective view thereof.
